(57) CLAIM

The ornamental design for combined glider chairs with table, as shown and described.

DESCRIPTION

FIG. 1 is a front perspective view of combined glider chairs with table showing our new design;

FIG. 2 is a top plan view;

FIG. 3 is a bottom plan view;

FIG. 4 is a front elevational view;

FIG. 5 is a rear elevational view; and,

FIG. 6 is an end view, the opposite end being a mirror image thereof.

The broken-line showing of the top portion of the glider chairs is for illustrative purposes only and forms no part of the claimed design.
